WELT MECHANISM FOR KNITTING MACHINES

Carlos A. Hepp, Palisade, N. J., assignor to Alfred Hofmann, Inc., West New York, N. J., a corporation of New Jersey

Application November 13, 1940, Serial No. 365,429

27 Claims. (Cl. 66—149)

The invention as herein disclosed comprises improvements in that portion of flat knitting machines for knitting full-fashioned hosiery by means of which the welt fold is tensioned and drawn away from the knitting needles.

The principal object of the invention is to provide an improved type of welt rod engaging mechanism that is of a simplified construction, more efficient and positive in operation, and which may be solely operated from a single wareroller shaft of a flat knitting machine.

Another object of the invention resides in the combination of two distinct types of operative means separately and independently operating, one through manipulation of a single wareroller shaft, and the other through the manipulation of a weight for the independent selective operation of the welt rod and welt bar of the knitting machine.

Other and more detailed objects of this invention will be apparent from the following detailed description of several embodiments thereof for a single section of a knitting machine when taken with the illustrations comprising the drawings attached hereto.

This invention resides substantially in the combination, construction, arrangement and relative location of parts, all as will be explained in full detail hereinafter.

In the accompanying drawings, sufficient parts of a single section of a flat-full-fashioned type knitting machine are shown to illustrate the invention as applied thereto.

Figure 1 represents, in perspective, the mechanism comprising one form of the invention;

Figure 2 is an enlarged top plan view of a portion of the mechanism comprising the invention;

Figure 3 is a side elevational view thereof;

Figure 4 is a plan view of a detail of this mechanism;

Figure 5 is a vertical, central, longitudinal, cross-sectional view of the detail;

Figure 6 is a view similar to that of Figure 2 of a modified construction;

Figure 7 illustrates a modification of the mechanism of Figure 4;

Figure 8 is a vertical, central, longitudinal, cross-sectional view through the mechanism of Figure 7;

Figure 9 is a cross-sectional view taken on the line 9—9 of Figure 8; and

Figure 10 is a cross-sectional view, similar to that of Figure 8, of a still further modified ar-

rangement for the portion of the mechanism illustrated.

In accordance with prior practice in this art, after the knitting of the welt fabric has proceeded to a sufficient length, the machine operator lays in the welt rods for each knitting section. The welt fabric is then turned back manually and the first course of loops is transferred back to the needles to form the welt. In order to lay in the welt rod it is necessary to place each of the take-up straps individually into correct engagement with the welt rod. These operations are accomplished manually, and in a multiple section machine it requires a considerable amount of time in order to engage all of the welt rods with their respective take-up straps.

This is particularly unavoidable because of the fact that the same take-up straps are used to draw off the welt bar with the welt fabric thereon in manual welt turning, which straps after being disengaged from the welt bar are hooked up with the welt rod to continue drawing off the knitted fabric.

However, with the advent of practically automatic welt turning devices, using separate draw-off means for the welt bar with the welt fabric thereon, this two-fold purpose of the ordinary draw-off mechanism operating through the wareroller and take-up straps has become obsolete.

It may be stated as a general object of this invention to provide means which is separate from the draw-off means acting on the welt bar, operable as and for the purpose of drawing off the welt fabric intermediately, prior to, and after the automatic turning of the welt, continuing the take-up functions by winding up the fabric on the warerollers. This apparatus also operates to position the take-up straps with welt rod hooks thereon in unison in all the sections of the machine, so that the operator after knitting a certain length of welt fabric simply lays in the welt rods since the take-up straps and welt rod receiving means have already been driven to a position to receive the welt rods by rotating the wareroller shaft in the direction opposite to the take-up direction.

An additional advantage of this arrangement lies in the fact that after completion of the knitting operations of a stocking, the latter may be unwound from the wareroller by the rotation of the shaft in the direction opposite to the take-up, without the draw-off bands or straps becoming loose and dangling into positions from which they are difficult to recover and rearrange. Dur-

ing this unreeling of the fabric the welt rod engaging members on the draw-off straps are driven towards their position ready for the next engagement of the welt rods therewith.

In other words, the device consists, with other constructive details, of a belt drive actuated exclusively by the rotative action of a single wareroller shaft to move all welt rod engaging members in either direction, towards or away from the needles substantially in a horizontal plane, and in a rotative motion substantially over the circumference of the wareroller.

A detailed description of the mechanism herein disclosed for accomplishing these objects in accordance with this invention will now be given. Only so much of a flat knitting machine section is illustrated in the drawings as is necessary to set forth the application of the invention thereto. Although the invention is shown applied to a knitting machine adapted for manual welt turning, it can equally well be applied to a machine having an automatic welt turning mechanism.

A single knitting section of a multi-section full-fashioned type flat knitting machine as illustrated in Figure 1 includes the table 1, common in such machines. The needle bar 2 supports the knitting needles 10 which, with the mechanism usually associated therewith but not shown in order to keep the disclosure simple, knits the welt and stocking fabric.

In accordance with the usual practice in manual welt turning mechanism, the welt bar 4 is provided with a plurality of welt bar hooks 5 on which the first course of loops of the welt fabric W is impaled. The hooks 5 are offset as indicated at 6 for a purpose which will be referred to later. The welt bar 4 is supported on guide rails 3 mounted on the table 1 by brackets 3' which hold the welt bar above the table, as shown, for movement towards and away from the needles 10. A strap 7 is connected to the welt bar 4 by a suitable fixture 11 and extends over a guide bar 9 so as to be above the wareroller 13. A weight 8 attached to the strap 7 acts to pull the welt bar 4 in "draw-off" direction and is so shown herein for diagrammatic illustration. The guides 3 are provided with stops 3'', against which the welt bar abuts after a predetermined length of welt fabric has been knitted so that the continued draw-off of the welt fabric may be resumed by the previously inserted welt rods in conjunction with the take-up mechanism described herein.

The usual wareroller shaft 12 common to all knitting sections of the knitting machine is provided, on which is mounted a wareroller 13 for each section of the machine. The shaft 12 extends throughout the entire length of the machine and is provided at one end with a reel 15 which is connected by a rope 17' to a weight 17 after the rope passes over a fixed pulley 16. The reel 15 which is connected in the usual practice to the shaft 12 by the usual ratchet and pawl mechanism (not shown), is subjected to a force by reason of the weight 17 acting through the rope 17' to cause clockwise rotation of the shaft 12.

The wareroller 13 is mounted for relative rotational movement of the shaft 12. Secured to the ends of the roller (see Figure 5) are the double pulleys or reels 14 which in turn are secured to the shaft 12 by means of coil springs 14'. As shown in Figures 2 and 3, the inner ends of the springs are attached to the shaft 12, as indicated at 14'', while the outer ends of the springs

are connected to the outer faces of the reels 14 by means of the pins 14''. Thus the wareroller is driven in a clockwise direction (viewed from the right hand end, Fig. 1) by the shaft 12 but through the springs 14' so that some relative movement therebetween can occur.

Each of the straps 18 is connected to the sections of each double reel 14 at both ends, as indicated at 18' and 18'' in Figure 2. The straps 10 each pass around pulleys 19 mounted on the shafts 19' and form upper and lower lengths as a result of their attachment to the reels 14. The shafts 19' are journaled in brackets 19'' mounted on the table 1. Extending between the straps 15 is a bar 20 which has slotted ends, as indicated at 20', so that it may be adjustably attached to the straps as clearly shown in Figures 2 and 3.

Secured on the bar 20 in any suitable manner, as for example by welding, are the welt hooks 21 which engage the ends of the welt rod 22 when it is in place. Engaging the lower length of each strap 18 is a tensioning device consisting of a pulley 23, a supporting yoke 24, and a spring 25 secured to one of the supports 26 of the machine. As indicated most clearly in Figure 3, the innermost flange of each double reel 14 is cut away, as indicated at 14''' so that when the welt rod is in the position indicated in Figure 4, that is, when it arrives at the wareroller, the 30 ends connecting rod 20 to the straps will lie in them.

After a sufficient length of the welt W has been drawn off, welt rod 22 is laid in and the welt is turned, that is the initial welt loops are transferred to the needles 10 by proper positioning of the welt bar 4, and welt hook 5 in relation to the needles 10 in accordance with the usual manual method of welt turning. In the form of mechanism the stops 3'' are adjustable to obtain the 40 desired length of welt fabric, and after the welt is turned, the welt bar is allowed to rest against them during the knitting of the leg portion. As the operation of knitting continues, the welt rod 21 lies in the turned welt fabric W and performs its function of drawing off the fabric as the knitting thereof continues.

The welt rod draw-off operating mechanism of this invention may be equally well used with machines in which the welt is automatically turned. In the case of automatic welt turning mechanism the welt bar does not perform the function of drawing off the entire length of the welt so that during an intermediate period the welt rod draw-off mechanism of this invention is used for drawing off the remainder of the welt. 50 In this form of operation after a portion of the welt is drawn off the welt bar no longer performs this function but is stationary against the stops 3''. The welt rod is laid in on the welt and as the knitting of the welt proceeds the welt rod 55 performs the draw-off function. The initial row of loops then engages the offset portions 6 of the welt hooks 5 where it remains as the welt rod moves rearwardly thereof to draw-off the welt in a fold under the welt bar. When the knitting 60 of the welt is completed the automatic welt turning mechanism performs its function by transferring the initial course of loops to the needles 10. The mechanism of this invention permits this operation because, as the welt bar is moved towards the needles 10 for the purpose of transferring the loops from the hooks 5 to the needles 10, the welt rod mechanism cooperates therewith by permitting the welt rod to move back towards 65 the needles as it must do because of the shortening

ing of the welt resulting from the turning thereof.

Thus, as will be apparent from the above description, the invention is applicable for use with either manual or automatic welt turning machines. It is likewise apparent that if the guides 3 are provided with the properly positioned stops 3" a similar operation with the manual welt turning mechanism of Figure 1 may be carried out. In this case the welt bar 4 would draw off the welt W until the bar engages the stops 3". The welt rod 21 would then be laid in over the welt and the welt rod draw-off mechanism would operate to continue drawing off the welt fabric at which time the first course of loops impaled on the welt hooks 5 would engage the offset portion 6 of these hooks to form a stop for them. When the knitting of the welt is completed it can then be turned manually in a manner similar to which it would be turned automatically in the case of the automatic welt turning machine.

In either type of machine as the knitting proceeds, the upper portions of the straps 18 are wound upon the pulleys 14, while the lower portions are unwound therefrom through the action of the usual ratchet and pawl device and the weight 17 on the shaft 12, so that the welt rod gradually moves toward the shaft 12, that is, in what may be termed the "draw-off" direction. In other words, as the upper portions of the strap 18 wind up on the reels 14, the lower portions unwind therefrom simultaneously without having to overcome any added force such as separate tensioning weights hereofore used with the positioning straps attached to the welt rod engaging members.

It will be clear by reference to Figure 7, and upon consideration, that the coil of each strap supplying the upper portions is decreasing in diameter as the lower portions are wound up, which will alternately cause a change in the relative length of the strap portions. In this form of the device, the change in length of the portions of the straps is compensated for by the tensioning means 25 engaging the lower portion of the straps. The wareroller 13 is resiliently connected to the shaft 12 in order not to impose too great a strain on the welt fabric during the initial stages of the knitting thereof after the welt rod takes over the draw-off action, at which time it is less stretchable because of its shortness than it will be as it grows longer.

The knitting of the leg portion of the stocking proceeds with the welt rod draw-off mechanism acting as before. The bar 20 moves into the notches 14c as indicated in Figure 4, where it stays while strap 18 continues to wind itself up on one portion of reel 14 and simultaneously to unwind itself from the other reel portion. As the knitting continues, the knitted fabric is rolled up on the wareroller and welt rod, which now lies parallel to the wareroller and close to it, as indicated in Figure 4. In other words, the fabric is gradually wrapped around the wareroller and also encloses the welt rod and bar 20 as will be apparent from a consideration of Figure 4.

The machine then continues to knit until the leg portion is finished. It goes without saying that there is sufficient strap coiled up in the outer grooves of the pulleys 14 at the beginning of the operation to permit the shaft 12 and wareroller 13 to rotate a sufficient number of revolutions to complete the knitting of a full length stocking.

It will be seen that the apparatus is so ar-

ranged and designed as to ensure an even draw-off tension in the fabric throughout the entire knitting operation. The apparatus is also designed and arranged to compensate for adjustment differences such as variations in the position of the welt rod hooks and the bar 20 on the strap members. It is of course apparent that other arrangements may be provided for the purpose of ensuring uniform tension in the fabric for different positions of the bar 20, as for example interposed coil spring tensioning members arranged substantially as described in United States Patent No. 1,545,953.

There is illustrated in Figure 3 a slight variation which may be of use. In this case the lower portion of the straps 18 are passed over the top of the table 1 and where necessary, although not shown, suitable anti-friction means such as rollers and slideways may be employed.

A modified construction is shown in Fig. 6. Only sufficient of this structure is shown to illustrate the modification. In this arrangement there is attached to the wareroller 13 at each end a spool or pulley 27 which has secured thereto at its ends a sufficiently long length of tightly coiled spring 28. The ends are attached to the spool 27 by means of clamps 28a and 28b, as clearly shown in the figure. The springs pass around the pulleys 19 on the shaft 19', as before, and the bar 20 is secured at its ends to the spring in any suitable manner, as by means of welding, as indicated at 20a.

It is to be noted in this case that the wareroller 13 is secured to the shaft 12 for rotation therewith. In this arrangement the tightly coiled spring 28 provides all the necessary resiliency to ensure a relatively constant tension in the fabric throughout its knitting. The mechanism is shown in Figure 6 in the position it would assume when the welt rod 22 is in the position shown in Figure 1. At this time there is a sufficient amount of the springs 28 coiled up on the spools 27 to permit a complete operation, at the end of which the portion shown on the spools 27 has unwound and has been replaced by the portion wound thereon from the upper course of the spring. It will be seen that as the portion on the spool unwinds it will be closely followed by the portion being wound onto it from the upper course of the spring.

The spools also are provided with the notches 27' corresponding to the notches 14c of the previous construction, so that this modification operates in a manner substantially similar to that previously described. If desired, but not necessarily so, the spools 27 may have peripheral spiral grooves in which the turns of the springs may nest. This construction is not necessary, however, since the turns from the upper course of the spring 28 follow closely into position as the turns from the lower course are unwound. Sufficient spring is provided, as in the case of the straps, to permit the knitting of a complete length of stocking.

It is particularly noteworthy that in this modified embodiment the loop of the coiled spring extending from the wareroller spool towards the table over roller 19 does not change in length during the winding or unwinding operation because of the fact that the simultaneous winding and unwinding of the coiled spring occurs over an even diameter of the spool. Consequently, no separate means need be employed to compensate for any length variations of the loop portion for the purpose of keeping it taut.

In both of these arrangements, after the stocking length is completed it is unwound from the wareroller, the welt rod disengaged from the hooks 21, and then disengaged from the welt loop. The warerollers are then rotated further in a counter-clockwise direction until the welt hooks which are moving in unison are put back in initial position. The apparatus is then ready to again go through the same cycle of operations.

In Figures 7 to 10, inclusive, there are illustrated several modified constructions with respect to the strap, spools or pulleys. In the construction of Figures 7 to 9, inclusive, the pulley is shown in two parts. The part 30 consists of a cylindrical portion having a flange, and is attached to the end of wareroller 13 as shown in Figure 8. It, in turn, is attached to the shaft 12 by means of a set screw 30'. A complementary portion 31 is rotatably mounted on the central hub 30' forming part of the portion 30. A torsion spring 33 lies in a recess in the outer face of the portion 31 and is attached thereto at one end by means of a pin 34 and at its other end by means of a pin 35 to a collar 32 which is secured on the shaft 12 by means of a set screw 36.

The collar 32 closes the recess and completes a housing for the spring 33. With this construction it will be apparent that the portion 31 is capable of relative rotational movement with respect to the shaft 12, the wareroller 13, the portion 30, and the collar 32, all of which parts are secured in the shaft 12. This provides a resilient arrangement to take up the slack of the straps arising because of the aforesaid variations in the length of the loop portions of said straps.

Figure 10 represents a modification of the previous construction. In this case the pulley consists of a part 37 secured to the wareroller 13 as shown. Secured on the shaft 12 adjacent the portion 37 is the other portion 38 which is attached to the shaft by the set screw 39. In this arrangement the wareroller 13 is not secured to the shaft 12. The portion 38 is recessed and houses a coil spring 40, the outer end of which is attached to the portion 37 by means of the pin 41, and the inner end is attached to the portion 38 by the pin 42. In this arrangement the wareroller 13 and the portion 37 are capable of relative rotational movement as a unit with respect to the shaft 12 and the portion 38 which is secured thereto.

In the constructions of Figures 7 and 10 the ends of the strap 18 are attached to the respective sections 30 and 31, and 37 and 38, as in the case of the arrangement of Figure 1. The straps 18 may be made of any suitable flexible material, preferably of the woven type, and may be either stretchable or non-stretchable. In place of the spring 28 of Figure 6, an equivalent strap would be one made of rubber, such as round rubber belting. In view of the various forms which the straps may take it is to be understood that the term in the claims is used in its broader sense to include all forms of strands suitable for the purpose.

From the above description it will be apparent to those skilled in the art that the subject matter of this invention is capable of embodiment in various physical forms, and I do not, therefore, desire to be limited by the disclosure herein but rather by the scope of the claims granted me.

What is claimed is:

1. In a full-fashioned hosiery knitting machine, a welt rod actuating mechanism comprising, in combination with a single wareroller shaft,

means for engaging the welt rod, and a single means actuated by said wareroller shaft for moving said first means in one direction to receive the welt rod, and then moving said first means in the opposite direction to actuate said rod in draw-off direction, said second means including a pulley mounted on said wareroller shaft and a folded strap engaging said first means and having its end portions wrapped in opposite directions upon said pulley.

5 2. In a full-fashioned hosiery knitting machine, a welt rod actuating mechanism comprising, in combination with a single wareroller shaft, means for engaging the welt rod, and a single means actuated by said wareroller shaft for moving said first means in one direction to engage the welt rod, and then moving said first means in the opposite direction to actuate said rod, said second means including a pair of pulleys mounted 15 on said wareroller shaft, and a strap having its end portions wrapped in opposite directions upon said pair of pulleys and having an intermediate portion secured to said means.

20 3. In a full-fashioned hosiery knitting machine, a welt rod actuating mechanism comprising, in combination with a single wareroller shaft, means for engaging the welt rod, and a single means actuated by said wareroller shaft for moving said first means in one direction to receive the welt 25 rod and then moving said first means in the opposite direction to move said rod, said second means including a pair of pulleys mounted on said wareroller shaft, and a yieldable strap having its end portions wrapped in opposite directions upon said pair of pulleys and having an intermediate portion secured to said means.

30 4. In a full-fashioned hosiery knitting machine, a welt rod actuating mechanism comprising, in combination with a single wareroller shaft, means for engaging the welt rod, a single means actuated by said wareroller shaft for moving said first means in one direction to engage the welt rod and then moving said first means in the opposite direction to actuate said rod, said second means including a pair of pulleys mounted on said wareroller shaft, and a strap having its end portions wrapped in opposite directions upon said pair of pulleys and having an intermediate portion secured to said means, and a tensioning device for holding the strap taut in the operation thereof.

35 5. In a multi-section full-fashioned knitting machine, in combination, a welt rod for each section, a single wareroller shaft, a separate device engaging each welt rod, and a separate single operating means for each device actuated solely by said wareroller shaft for moving the associated device in the opposite direction to actuate said rod, said means including a pair of pulleys mounted on said wareroller shaft, and a strap having its end portions wrapped in opposite directions upon said pair of pulleys and having an intermediate portion secured to said device.

40 6. In a multi-section full-fashioned knitting machine, in combination, a welt rod for each section, a single wareroller shaft, a separate device engaging each welt rod, a separate single operating means for each device actuated solely by said wareroller shaft for moving the associated device in one direction to engage the welt rod, and for moving said device in the opposite direction to actuate said rod, said means including a pair of pulleys mounted on said wareroller shaft, and a strap having its end portions wrapped in opposite directions upon said pair of pulleys and having an intermediate portion secured to said device.

cured to said device, and a tensioning device for holding the strap taut in the operation thereof.

7. In a full-fashioned hosiery knitting machine, in combination, a welt rod, a wareroller shaft and a wareroller mounted thereon, a pair of pulleys mounted on each end of the wareroller, a pair of reels arranged contiguous to said welt rod, a pair of flexible straps each having an intermediate portion passed around one of said reels and its end portions wrapped in opposite directions around a pair of said pulleys, a bar connecting the straps together, and hooks on said bar for engagement with the welt rod.

8. In a full-fashioned hosiery knitting machine, in combination, a welt rod, a wareroller shaft and a wareroller mounted thereon, a pair of pulleys yieldably mounted on each end of the wareroller, a pair of reels arranged contiguous to said welt rod, a pair of flexible straps each having an intermediate portion passed around one of said reels and its end portions wrapped in opposite directions around a pair of said pulleys, a bar connecting the straps together, hooks on said bar for engagement with the welt rod, and tensioning devices engaging an intermediate portion of each strap for holding the same taut.

9. In a full-fashioned hosiery knitting machine, in combination, a welt rod, a wareroller shaft and a wareroller mounted thereon, a pair of pulleys yieldably mounted on each end of the wareroller, a pair of reels arranged contiguous to said welt rod, a pair of flexible straps each having an intermediate portion passed around one of said reels and its end portions wrapped in opposite directions around a pair of said pulleys, a bar connecting the straps together, hooks on said bar for engagement with the welt rod, tensioning devices engaging an intermediate portion of each strap for holding the same taut, a welt bar having a series of welt hooks, guide rails upon which said welt bar is mounted for sliding movement, adjustable stops on said rails to limit the movement of said welt bar, a strap secured to said welt bar, and a weight secured to said strap.

10. In a full-fashioned hosiery knitting machine, in combination, a welt rod, a wareroller shaft and a wareroller mounted thereon, a pair of pulleys mounted on the wareroller, a pair of reels arranged contiguous with said welt rod, a pair of flexible straps each having an intermediate portion passed around one of said reels and its end portions wrapped in opposite directions around one of said pulleys, a bar connecting the straps together, hooks on said bar for engagement with the welt rod, tensioning devices engaging an intermediate portion of each strap for holding the same taut, a welt bar having a series of welt hooks, guide rails upon which said welt bar is mounted for sliding movement, stops on said rails to limit the movement of said welt bar, a strap secured to said welt bar, a weight secured to said strap, and a tensioning device for each strap engaging an intermediate portion thereof.

11. In a full-fashioned stocking knitting machine, in combination, a bank of knitting needles, means coacting with said knitting needles for the knitting of a welt fabric and the turning thereof, and a mechanism for tensioning the welt fabric consisting of a welt rod, a wareroller shaft, a pair of pulleys yieldably mounted on each end of the wareroller shaft, a pair of reels arranged contiguous to said welt

rod, a pair of flexible straps each having an intermediate portion passed around one of said reels and an end portion wrapped in opposite directions around said pair of pulleys, and hooks connected to said straps and adapted for engagement and disengagement with the welt rod.

5 12. In a full-fashioned knitting machine, a wareroller shaft, a pair of strap loops supported at their bights, means for resiliently attaching both ends of each strap to said shaft so that upon rotation of said shaft one end of each strap coils about it as its other end uncoils, and welt rod engaging means mounted on said straps.

15 13. In a full-fashioned hosiery knitting machine, in combination, a single wareroller shaft, a welt rod, and mechanism for operating the welt rod including a pair of straps for engagement with the welt rod, each strap having both end portions attached to the wareroller shaft.

20 14. In a full-fashioned hosiery knitting machine, a single wareroller shaft, a welt rod, mechanism for operating the welt rod including a pair of straps for engagement with the welt rod, each strap having both end portions wrapped about and attached to the wareroller shaft, and welt rod engaging hooks connected to the straps.

25 15. In a full-fashioned hosiery knitting machine, in combination, a single wareroller shaft, a welt rod, mechanism for operating the welt rod including a pair of straps for engagement with the welt rod, each strap having both end portions wrapped about and attached to the wareroller shaft, welt rod engaging hooks connected to the straps, a welt bar, and means independent of said straps for sliding said welt bar.

30 16. In a full-fashioned hosiery knitting machine, in combination, a single wareroller shaft, a welt rod, mechanism for operating the welt rod including a pair of straps for engagement with the welt rod, each strap having both end portions wrapped about and attached to the wareroller shaft, welt rod engaging hooks connected to the straps, a welt bar, and means independent of said straps for sliding said welt bar, said means consisting of a strap and a weight connected to the strap.

35 17. A welt rod take-up device comprising, in combination with a shaft, a folded strap for connection with the welt rod and having both end portions solely secured to said shaft whereby upon rotation of the shaft in opposite directions the strap is moved in opposite directions.

40 18. A welt rod take-up device comprising, in combination with a shaft, a folded strap for connection with the welt rod and having both end portions solely secured to said shaft whereby, upon rotation of the shaft in opposite directions, the strap is moved in opposite directions, a welt bar, a strap secured to the welt bar, and a weight secured to the strap.

45 19. In a multi-section full-fashioned knitting machine, in combination, a welt rod for each section, a single wareroller shaft, a separate device engaging each welt rod, and a separate single operating means for each device actuated solely by said wareroller shaft for moving the associated device in the opposite direction to actuate said rod, said means including a pair of pulleys mounted on said wareroller shaft, and a strap having its end portion wrapped in opposite directions upon said pair of pulleys and having an intermediate portion secured to said device, a

welt bar for each section, and means for drawing and tensioning said welt bar.

20. In a multi-section full-fashioned knitting machine, in combination, a welt rod for each section, a single wareroller shaft, a separate device engaging each welt rod, a separate single operating means for each device actuated solely by said wareroller shaft for moving the associated device in one direction to engage the welt rod, and for moving said device in the opposite direction to actuate said rod, said means including a pair of pulleys mounted on said wareroller shaft, and a strap having its end portions wrapped in opposite directions upon said pair of pulleys and having an intermediate portion secured to said device, a tensioning device for holding the strap taut in the operation thereof, a welt bar for each section, a strap attached to each welt bar, and a weight attached to each strap.

21. In a full-fashioned hosiery knitting machine, in combination, a welt rod, a wareroller shaft and a wareroller mounted thereon, a pair of pulleys mounted on each end of the wareroller, a pair of reels arranged contiguous to said welt rod, a pair of flexible straps each having an intermediate portion passed around one of said reels and its end portions wrapped in opposite directions around a pair of said pulleys, a bar connecting the straps together, hooks on said bar for engagement with the welt rod, a welt bar, a strap attached to the welt bar, and a weight attached to the strap.

22. In a full-fashioned hosiery knitting machine, in combination, a welt rod, a wareroller shaft and a wareroller mounted thereon, a pair of pulleys yieldably mounted on each end of the warerollers, a pair of reels arranged contiguous to said welt rod, a pair of flexible straps each having an intermediate portion passed around one of said reels and its end portions wrapped in opposite directions around a pair of said pulleys, a bar connecting the straps together, hooks on said bar for engagement with the welt rod, tensioning devices engaging an intermediate portion of each strap for holding the same taut, a welt bar, and means for drawing said welt bar under tension.

23. In a full-fashioned stocking knitting machine, in combination, a bank of knitting needles,

means coasting with said knitting needles for the knitting of a welt fabric and the turning thereof, a mechanism for tensioning the welt fabric consisting of a welt rod, a wareroller shaft, a pair of pulleys yieldably mounted on each end of the wareroller shaft, a pair of reels arranged contiguous to said welt rod, a pair of flexible straps each having an intermediate portion passed around one of said reels and an end portion wrapped in opposite directions around said pair of pulleys, and hooks connected to said straps and adapted for engagement and disengagement with the welt rod, a welt bar, a strap attached to the welt bar, and a weight attached to the welt bar strap.

24. In a full-fashioned hosiery knitting machine, in combination, a wareroller shaft, a welt rod, and flexible elements for attachment to said rod, each element having two end portions wrapped about said shaft whereby rotation of the shaft in opposite directions moves the element in opposite directions for the engagement with, and operation of, the welt rod.

25. In a full-fashioned hosiery knitting machine, in combination, a wareroller shaft, a welt rod, and coil springs for attachment to said rod, each spring having two end portions wrapped about said shaft whereby rotation of the shaft in opposite directions moves the spring in opposite directions for the engagement with, and operation of, the welt rod.

26. In a full-fashioned hosiery knitting machine, in combination, a wareroller shaft, a welt rod, a reel spaced from said wareroller shaft and rotatable independently thereof, a coil spring passing around said reel and wareroller shaft and operated by said shaft, and welt rod engaging hooks connected to said coil spring.

27. In a full-fashioned hosiery knitting machine, in combination, a shaft, a welt rod, a reel, a coil spring passing around said reel and having end portions wrapped in opposite directions about said shaft whereby upon rotation of said shaft in opposite directions the coil spring is moved in opposite directions, and means connected to said spring for engagement and disengagement with the welt rod.
